UNITED STATES PATENT OFFICE

HANS LESSING, OF BERLIN-CHARLOTTENBURG, GERMANY

FOUNTAIN PEN

Application filed September 20, 1926, Serial No. 136,517, and in Germany September 25, 1925.

This invention relates to fountain pens, and more particularly to a fountain pen, which consists of two parts made to be rotary to each other, and in which the passage of the ink from the main barrel to the front barrel carrying the nib is capable of being regulated.

According to the invention the adjustment or closure plate is furnished with several openings, and is connected with the front barrel by means of a ring of soft material, which simultaneously acts as a washer. The said ring, which is preferably composed of soft rubber, is employed as a coupling member between the front barrel and the closure plate, the two latter parts being for this purpose provided with projections.

The invention will now be described more fully with reference to the accompanying drawing, in which

Fig. 1 is a section through a possible form of embodiment of the pen.

Fig. 2 is a section on the line 2—2 of Fig. 1, with the passages open, and

Fig. 3 a similar view to Fig. 2 with the passages closed.

Referring to the drawing 10 is the main barrel, which is closed at its upper end by means of a plate 11. This plate may consist of one piece with the main barrel, or may also be fitted separately. On the upper set-off edge 12 of the barrel 10 is mounted the front barrel 13, which is capable of rotation. The front barrel 13 is set off in the interior, i. e., is furnished with an inner shoulder, and in this part is mounted the soft rubber ring 14. Below the rubber ring 14 is situated the closure plate 15, which is furnished with holes 16. The closure plate 11 of the main barrel 10 possesses corresponding holes 17 which, as shown in Fig. 2, may be moved into alignment with the holes 16, in order to allow the ink to pass through into the front barrel.

The inner set-off edge of the front barrel 13 is provided with projections 18 which, as shown in Fig. 1 project into the upper edge of the soft rubber ring when the two barrels are set together. The edge portion on the upper face side of the plate 15 is also furnished with projections 18, which thrust into

the lower edge of the rubber ring. The main barrel is provided on its extreme periphery with grooves 19, in which engage pins 20, which are mounted on the front barrel above the lower edge thereof.

The soft rubber ring 14 forms a washer for preventing the ink from passing outwardly after its passage through the opening provided. Due to the arrangement of the groove and pin connection between the two barrels the soft rubber ring also presses the adjustment plate 15 on to the closure plate 11, so that a tight closure is also ensured at this point.

In addition, the ring constitutes the coupling member between the main and front barrels.

What I claim as new and desire to secure by Letters Patent is:

In a fountain pen, a main barrel, a front barrel capable of rotation in relation to the said first barrel, a closure disc at the end of the said first barrel, a closure plate seated within the said second barrel and resting over the said closure disc, a rubber ring washer mounted within the said second barrel pressing the said closure plate on to the said closure disc, projections on the interior of the said second barrel and projections on the edge of the said closure plate, the said projections serving to firmly engage the said washer, a plurality of holes in the said closure disc, and corresponding holes in the said closure plate.

In testimony whereof I have affixed my signature.

HANS LESSING.
